CHARLES J. SYMMONDS, OF CHEVY CHASE, MARYLAND

ARTICLE OF FURNITURE OF THE FOLDING TYPE

Application filed September 27, 1932. Serial No. 635,041.

(GRANTED UNDER THE ACT OF MARCH 3, 1883, AS AMENDED APRIL 30, 1928; 370 O. G. 757)

This invention described herein may be manufactured and used by or for the Government for governmental purposes, without the payment to me of any royalty thereon.

5 This invention relates to an article of furniture of the folding type, more particularly it is directed to a folding, locking and leg bracing mechanism for an article of furniture ordinarily having a flat top.

10 One of the objects of my invention is to provide a folding, locking and leg bracing mechanism which is adapted to be easily and quickly applied to an article of furniture such as a table or the like, to provide means for readily folding and unfolding the legs thereof, also for rigidly bracing said legs when in an unfolded or operative position and for locking said leg folding and unfolding mechanism including said legs into position as usage requires.

Another object of my invention is to provide a folding, locking and leg bracing mechanism for an article of furniture such as a table or the like which may be applied to the 25 article of furniture for easily and quickly folding or unfolding the legs thereof independently of the top of said article of furniture, thereby permitting different tops for the furniture to be substituted without interfering with the working parts of said folding, locking and leg bracing mechanism.

Another object of my invention is to provide a folding, locking and leg bracing mechanism for an article of furniture which is 30 simple in operation, cheap in construction and which is not liable to get out of order.

With the above and other objects in view the invention specifically consists in features of construction, arrangement, and operation of parts which will hereinafter appear. For purposes of illustration the invention will be described and claimed with reference to the accompanying drawings in which like members distinguish like parts and in which:

45 Fig. 1 is a perspective view of my folding table inverted with the legs thereof in operative position having my invention applied thereto;

50 Fig. 2 is a cross-sectional view thereof taken on line 2—2 of Fig. 1, illustrating one set

of the legs of the table in operative position and another set thereof in a folded or inoperative position;

55 Fig. 3 is a perspective detail view of a locking device for holding the legs of the table in both folded and open positions;

Fig. 4 is a bottom plan view of Fig. 1; and

Fig. 5 is a cross-sectional view taken on line 5—5 of Fig. 4, looking in the direction 60 of the arrows.

65 In the illustrated embodiment characterizing my invention, A indicates generally an article of furniture here illustrated in the form of a table to which my invention may be applied for folding or unfolding the pairs of legs 1 and 2, respectively.

70 The table A comprises a top supporting frame 3 having depending side rails 4 and 5 which are joined together at their ends by means of corner irons 6 which are attached to the side rails 4 and 5 by any suitable means such as screws 7, transversely extending across the side rails 4 and suitably connected thereto by their ends are stabilizing beams or cross braces 8 which are parallel to and spaced from the side rails 5.

75 Mounted on the supporting frame 3 is a table top 9 having flanges 10 extending therefrom adjacent the side rails 4 and 5 of the supporting frame 3. The flanges 10 of the table top 9 are joined at their ends by means of metallic angle straps 11 which are suitably connected thereto. The flanges 10 are fastened to the sides of the rails 4 and 5 of the supporting frame 3 by any suitable means such as screws 12 or the like.

80 Cross bars 13L and 13R are provided between the legs 1 and 2, wherein L denotes the left hand side and R the right hand side of the table A. The bars 13L and 13R constitute 85 pivot bars and are provided at each end with reduced rounded ends forming pivots 14 which are adapted to project through an aperture provided in the inner end of each of the legs 1 and 2 and be pivotably secured to the side rails 5 of the supporting frame 3 by means of securing means 15.

90 The legs 1 and 2 are further secured to the pivot bars 13L and 13R by means of fixed braces 16 and also by means of plates 17L and 17R, which are made of metal or any other suitable material.

Each of said plates 17L and 17R may be provided with an aperture 18, through which the pivots 14 of the pivot bars 13L and 13R may project and are provided with extensions 19 having pivotable connection with links 20L and 20R. Each of the links 20L and 20R are pivotably connected at the other end to stub links or equalizers 21L and 21R. The other end of each stub link or equalizer 21L and 21R is pivoted to a substantially triangular-shaped offset portion 22 of links 23L and 23R, which is pivoted to the cross braces 8 at 24 and forms part of collapsible braces 25L and 25R, the other end of the collapsible braces 25L and 25R constituting links 26L and 26R, which are pivoted at 27 to each of the links 23L and 23R and at its other end to its respective leg.

A stop 28 is provided as an extension of each link 26L and 26R to abut against the table side of links 23L and 23R.

The above description applies equally well to any one of the linkages of each of the four corners of the table.

For purposes of my invention I provide an operating or control linkage which is connected to all of said corner or leg moving linkages so that upon movement thereof the two right legs 2 will be opened up into operative position first and thereafter the two left legs 1 upon further movement of the control linkage will be opened up to their normal extended or operative position. This control linkage comprises a substantially bail or U-shaped member 29 which is made of resilient material and is adapted to be held in a locked or latched position by means of a latch 30 having one portion 31 thereof connected to the control linkage 29 and other portions comprising complementary members 32L and 32R thereof connected to the bottom of the table top 9 and suitably spaced from each other.

The control linkage 29 is pivotably connected at its remote ends to links 33R and pivotably connected at points intermediate said ends and the common connecting portion or handle H to links 33L. It is to be noted that the other end of links 33L and 33R are connected pivotably to the centers or the middle of the stub links 21L and 21R, which therefore constitute equalizer bars. In order to guide the action of the control linkage 29, a friction bearing and guide member 34 provided with a guide aperture 35 through which the links 33R extends and which are adapted to be frictionally held stationary or move longitudinally thereon upon the operation of the control linkage 29 is secured to the cross braces 8 of the table.

To operate my device I proceed as follows: I first grasp the folded table and place it in an inverted position so that the obverse side of the table is presented to the operator. Next the common bail-shaped member 29 is

pushed inwardly against the spring action thereof to release the latch 30 from its complementary latch member 32L. By pushing on the common bail-shaped member 29 it is caused to be sprung inwardly which causes the ends thereof to force the links 33R against the outside edge of the guide aperture 35 provided in each of the friction bearing and guide members 34. The hand then orients the common bail-shaped member 29 in an accurate path in a clockwise direction. Continued motion of the common bail-shaped member causes the links 33R to move longitudinally in the friction bearing and guide members 34 and constrains the linkage and equalizers to raise the right hand leg members which attain their fully extended location when the angle described is substantially tantamount to 90°. The left hand leg members are acted upon by the constrained linkages and equalizers when the common bail-shaped member is operated and the right and left hand leg members are in a folded position thereby causing the left hand leg members to assist in raising the right hand leg members. Extenuated action of the common bail-shaped member 29 then acts on the linkages and equalizers of the left hand leg members with a delayed action to raise them to their fully extended location. The common bail-shaped member is now snapped into its latch position with the complementary latch member 32R. The collapsible braces hold the unitary leg members in extended position and prevent the collapse thereof. Upon inversion of my table it is ready for use.

To fold the leg members from a raised or unfolded position to a lowered or folded position the common bail-shaped member 29 is again grasped by the hand and pulled inwardly against the spring action thereof to unlock the latch 30 from its complementary latch member 32R. This action causes the ends of the common bail-shaped member 29 to force the links 33R against the outside edges of the guide aperture 35 provided in the friction bearing and guide members 34 thereby causing the links 33R to have a frictional connection therewith to hold the right hand leg members in extended position while the left hand leg members are being lowered to a folded or collapse position. The action of the common bail-shaped member also causes the links 33R to be held in a stationary position thus contributing to the frictional action above referred to for holding the right hand leg members in fully extended position. The hand then orients the common bail-shaped member 29 in an accurate path in a counter-clockwise direction. The pivots which are common to the links 33R and the ends of the common bail-shaped member 29 remaining fixed while the common bail-shaped member is being operated.

By virtue of the above mentioned spring effect of the common bail-shaped member 29 on the links 33R when released by the latch 30 from its complemental latch-member 32R, the action thereof is transmitted to the links 33L which in turn acts on the linkage for the left hand leg members to lower the left hand leg members into folded position. Ex-
5 tenuated motion of the common bail-shaped member after the left hand leg members have been folded to their fully closed position causes the pivoted point of the equalizers 21L and the ends of the links 33L to become fixed which in turn causes the links 33L which
10 are connected by their other end to the bail-shaped member 29 to act on the bail-shaped member as a revolving or moving fulcrum. The restraining action of the fixed equalizers 21L and the links 33L causes the action of
15 the bail-shaped member 29 to be transmitted back to the links 33R which in turn act on the linkage for the right hand leg members to fold them into inoperative or folded position, the right hand leg members folding
20 upon the left hand leg members. The latch 30 of the common bail-shaped member 29 is now snapped into its latch position with the complemental latch member 32L. The table
25 is now in an inoperative condition for putting it away in a small space for future use.

It will thus be seen that I have invented a highly novel, simple and efficient article of furniture of the folding type which is well adapted for all the purposes designated.
25 Even though I have herein shown and described my device as comprising certain structural elements, it is nevertheless to be understood that changes may be made therein without departing from the spirit or scope
30 of my invention, which broadly comprises a frame having ends, a unitary leg member pivoted thereto at each end, common means connected to said unitary leg members for extending first one unitary leg member into
35 and then the other unitary leg member into extended position upon continual movement of said means, said means comprising pivotal equalizing bars, and a combination bail link and branching linkages connected to said
40 legs, said branching linkages comprising links having one end of each pivotably connected to said equalizing bars, links having one end of each pivotably connected to said pivotal equalizing bars, and the other ends thereof pivotably connected to said legs, collapsible braces each pivoted to its respective leg at one end and to said pivotal equalizing bars and said frame at the other end thereof, guide means secured to said frame and having
45 a guiding surface in contact with certain of said branching linkages, and wherein said unitary leg member comprises a common pivoted rod having legs fixably secured thereto near its ends, brace members comprising a bar fixably secured at one end to its respec-

tive leg and at the other end to said rod, and latch means for holding said common means in locked position either when the unitary leg members are in a folded or unfolded position.
50

Now that I have disclosed my invention what I claim as new and useful is:

1. An article of furniture comprising a frame having ends, a unitary leg member pivoted thereto at each end, common control means, leg moving means connected to said unitary leg members and said common control means, said common control means acting upon said leg moving means to first move one of said unitary leg members and then
75 the other of said unitary leg members into folded or unfolded position.

2. An article of furniture comprising a frame having ends, a unitary leg member pivoted thereto at each, control linkage means, leg moving links connected to said unitary leg members and said control linkage means, said control linkage means acting upon said leg moving links to first move one of said unitary leg members and then
85 the other of said unitary leg members into a folded or unfolded position.

3. An article of furniture comprising a frame having ends, a unitary leg member pivoted thereto at each end, control linkage means, leg moving links connected to said unitary leg members and said control linkage means, a friction bearing and guide member connected to certain of said leg moving links and said table, said control linkage means
90 acting upon said leg moving links to first move one of said unitary leg members and then the other of said unitary leg members into a folded or unfolded position.

4. An article of furniture comprising a frame having ends, a unitary leg member pivoted thereto at each end and common means connected to said unitary leg members for extending first one unitary leg member and then the other unitary leg member into
100 extended position upon continual movement of said means, said means comprising pivotal equalizing bars, and a combination bail link and branching linkage connected to said legs, said branching linkage comprising links having one end of each pivotably connected to said equalizing bars and links having one end of each pivotably connected to said pivotal equalizing bars and the other ends thereof
110 pivotably connected to said legs.

5. An article of furniture comprising a frame having ends, a unitary leg member pivoted thereto at each end, common means connected to said unitary leg members for extending first one unitary leg member and then the other unitary leg member into extended position upon continual movement of said means, said means comprising pivotal equalizing bars, and a combination bail link and branching linkages connected to said
120

legs, said branching linkages comprising links having one end of each pivotably connected to said equalizing bars and links having one end of each pivotably connected to 5 said pivotal equalizing bars and the other ends thereof pivotably connected to said legs and collapsible braces, each pivoted to its respective leg at one end and to said pivotal equalizing bars and said frame at the other 10 end thereof.

6. An article of furniture comprising a frame having ends, a unitary leg member pivoted thereto at each end, common means connected to said unitary leg members for 15 extending first one unitary leg member and then the other unitary leg member into extended position upon continual movement of said means and latch means for holding said common means in locked position either when 20 the unitary leg members are in a folded or unfolded position.

7. An article of furniture comprising a frame having ends, a unitary leg member pivoted thereto at each end, common means 25 connected to said unitary leg members for extending first one unitary leg member and then the other unitary leg member into extended position upon continual movement of said means, said means comprising a combination bail link and branching linkages connected to said legs and guide means secured to said frame and having a guiding surface in contact with certain of said branching linkages. 30

35 8. An article of furniture comprising a frame having ends, a unitary leg member pivoted thereto at each end, common means connected to said unitary leg members for extending first one unitary leg member and 40 then the other unitary leg member into extended position upon continual movement of said means wherein said unitary leg member comprises a common pivoted rod having legs fixably secured thereto near its ends and brace members, each of said brace members comprising a bar fixably secured at one end to its respective leg and at the other end to said rod. 45

50 9. An article of furniture comprising a frame having ends, a unitary leg member pivoted thereto at each end, common means connected to said unitary leg members for extending first one unitary leg member and then the other unitary leg member into extended position upon continual movement of 55 said means, said means including pivotal equalizing bars, and collapsible braces, each pivoted to its respective leg at one end and to said equalizing bars and said frame at the other end thereof. 60

10. An article of furniture comprising a frame having ends, a unitary leg member pivoted thereto at each end, common means connected to said unitary leg members for 65 extending first one unitary leg member and

then the other unitary leg member into extended position upon continual movement of said means, said means comprising pivotal equalizing bars, and a combination bail link and branching linkages connected to said legs, said branching linkages comprising links having one end of each pivotably connected to said equalizing bars, links having one end of each pivotably connected to said pivotal equalizing bars and the other ends 70 thereof pivotably connected to said legs, collapsible braces, each pivoted to its respective leg at one end and to said pivotal equalizing bars and said frame at the other end thereof and latch means for holding said common means in locked position either when the unitary leg members are in a folded or unfolded position. 75

11. An article of furniture comprising a frame having ends, a unitary leg member pivoted thereto at each end, common means 80 connected to said unitary leg members for extending first one unitary leg member and then the other unitary leg member into extended position upon continual movement of 85 said means, said means comprising pivotal equalizing bars, and a combination bail link and branching linkages connected to said legs, said branching linkages comprising links having one end of each pivotably connected to said equalizing bars, links having one end of each pivotably connected to said pivotal equalizing bars and the other ends 90 thereof pivotably connected to said legs, collapsible braces each pivoted to its respective leg at one end and to said pivotal equalizing bars and said frame at the other end thereof, guide means secured to said frame and having a guiding surface in contact with certain of said branching linkages, and latch means for holding said common means in locked position either when the unitary leg members are in a folded or unfolded position. 100

12. An article of furniture comprising a frame having ends, a unitary leg member pivoted thereto at each end, common means connected to said unitary leg members for extending first one unitary leg member and then the other unitary leg member into extended position upon continual movement of 105 said means, said means comprising a combination bail member and branching linkages connected to said legs, guide means secured to said frame and having a guiding surface in contact with certain of said branching linkages and latch means for holding said common means in locked position either when the unitary leg members are in a folded or unfolded position. 110

13. An article of furniture comprising a frame having ends, a unitary leg member pivoted thereto at each end, common means connected to said unitary leg members for extending first one unitary leg member and then the other unitary leg member into ex- 115

tended position upon continual movement of said means, said means comprising a bail link and branching linkages connected to said legs, guide means secured to said frame and 5 having a guiding surface in contact with certain of said branching linkages, wherein said unitary leg member comprises a common pivoted rod having legs fixably secured thereto near its ends, brace members, each 10 of said brace members comprising a bar fixably secured to one end to its respective leg and at the other end to said rod, and latch means for holding said common means in locked position either when the unitary leg 15 members are in a folded or unfolded position.

14. An article of furniture comprising a frame having ends, a unitary leg member

pivoted thereto at each end and common means connected to said unitary leg members for extending first one unitary leg member and then the other unitary leg member into extended position upon continual movement of said means, said means comprising a combination bail link and branching linkages connected to said legs, guide means secured to said frame and having a guiding surface in contact with certain of said branching linkages, wherein said unitary leg member comprises a common pivoted rod having legs fixably secured thereto near its ends and brace members, each of said brace members comprising a bar fixably secured at one end to its respective leg and at its other end to said rod. 70 75 80
